UNITED STATES PATENT OFFICE

167,425

BRACELET OR THE LIKE

John V. Saccone, Lodi, N. J., assignor to Swiss Watch Dial Co., Inc., New York, N. Y., a corporation of New York

Application April 7, 1952, Serial No. 19,221

Term of patent 14 years

(Cl. D45—4)

To all whom it may concern:

Be it known that I, John V. Saccone, a citizen of the United States, residing in Lodi, county of Bergen, State of New Jersey, have invented a new, original, and ornamental Design for a Bracelet or the like, of which the following is a specification, reference being had to the accompanying drawing, forming part thereof.

On the drawing,

Fig. 1 is a top plan view of a bracelet, showing my new design, with the conventional bottom links and conventional clasp shown in broken lines and with a portion of the bracelet broken away for convenience of illustration only;

Fig. 2 is a top plan view similar to Fig. 1 but illustrating the links in an expanded position;

Fig. 3 is a top plan view of a single top link; and

Figs. 4 and 5 are side elevational and end views, respectively, on a single link.

I claim:

The ornamental design for a bracelet or the like, substantially as shown and described.

JOHN V. SACCOME.
